UNITED STATES PATENT OFFICE.

FRANK E. GARBUZZ, OF LOS ANGELES, CALIFORNIA.

ELLIPTIC IRIS.

1,302,359.

Specification of Letters Patent. Patented Apr. 29, 1919.

Application filed July 15, 1918. Serial No. 245,111.

To all whom it may concern:

Be it known that I, FRANK E. GARBUZZ, a citizen of the United States, residing at Los Angeles, in the county of Los Angeles 5 and State of California, have invented a new and useful Elliptic Iris, of which the following is a specification.

My invention relates to the art of photography, being more particularly an iris for 10 use on motion picture cameras by means of which the field of the camera is elliptical in shape, the size of the opening in the iris being regulated at the will of the operator. I am aware that iris diaphragms have been 15 used on cameras in which the iris constituted a circle, but by the use of an iris having an elliptical opening therein a much more artistic effect can be obtained, particularly where there are one or two subjects, one or 20 more of which would be entirely cut out by using an iris circular in shape.

The principal object of my invention is to produce an iris of simple form and construction in which the opening is elliptic in 25 shape and the provision of simple means for the operation of the same.

Referring to the drawings, which are for illustrative purposes only.

Figure 1 is a face view of an iris embodying a form of my invention, a portion 30 of the same being broken away to better show the form of the leaves.

Fig. 2 is a vertical sectional view on line 2—2, Fig. 1.

35 The device consists of a stationary ring 10, to the outer edge of which is secured by means of suitable pins 11 a circular band or flange 12 which extends above the face of the stationary ring. Superimposed upon 40 each other on the face of the stationary ring is a series of leaves 13, each leaf being pivotally mounted on a pin 14 supported in a rotatable ring 15, which rotates on the inner face of the circular band 12, being retained 45 therein by a retaining ring 16 threaded into the circular band 12, and having a flange 17 which extends over the edge of the circular band 12, as shown in Fig. 2.

Each of the leaves also is provided with 50 a stud 18 which extends into a curved cam slot 19 formed in the face of the stationary ring 10, it being understood that there is a separate curved slot 19 for each stud 18.

The leaves 13 are formed with a curved 55 inner edge indicated at 20, the curve of each

of the leaves being a developed curve and different from each other with the exception that the leaves on one half of the iris have each a correspondingly shaped leaf on the opposite half of the iris, the pivotal points 60 of each pair of leaves having the same shaped inner edge, being directly opposite to each other.

The stationary ring 10 is provided with a central opening 22 which is elliptical in 65 shape, the longest axis of such opening being of the same diameter as a circular opening 23 formed in the rotatable ring 15. The circular band 12 is provided with a slot 25 through which extends an operating arm or 70 pin 26, the inner end of such arm extending into the rotatable ring 15, as shown in Fig. 2.

The size of the iris is determined by the position of the rotatable ring 15 with relation to the stationary ring and the movement of the rotatable ring by means of the operating arm 26 causes the respective leaves to be swung inwardly or outwardly according to the direction of movement of the operating arm due to the fact that the studs 75 80 on the respective leaves are guided by their respective slots, thereby causing the leaves to swing inwardly or outwardly according to the direction of movement of the rotatable ring. The slots 19 are curved in shape, being eccentric to the center of the iris and are arranged so that the leaves will proportionately move to retain the opening in the iris elliptical in shape from its largest 85 to its smallest diameter, the opening in the 90 iris as shown in Fig. 1 being substantially at its intermediate point or size.

What I claim is:

1. An elliptic iris diaphragm consisting of a stationary ring, a rotatable ring mounted 95 on said stationary ring, a plurality of pairs of leaves interposed between said rings, a pin on each leaf extending into the rotatable ring to pivotally mount its associated leaf on the rotatable ring, each of said leaves having 100 a curved inner edge, the curvature of the inner edge of the leaves in each pair being substantially identical and different from the curvature of the inner edge of the other leaves, said rotatable ring having a series of 105 curved slots therein, one for each leaf, the slots for each pair of like leaves being identical and such slots being eccentric to the center of the iris, a stud on each leaf extending into one of the slots, and means for 110

moving the rotatable ring to vary the position of the leaves.

2. An elliptic iris diaphragm consisting of a stationary ring, a rotatable ring, a plurality of pairs of leaves interposed between said rings, each leaf being pivotally mounted independent of each other on the rotatable ring, the leaves in each pair being substantially identical in outline but different from the outline of all the other leaves, said stationary ring having cam slots therein eccentrically arranged with respect to the center of the iris, a stud on each leaf extending into one of the cam slots in the stationary ring, and means for operating the rotatable ring.

3. An elliptic iris diaphragm consisting of a stationary ring, a rotatable ring, a plurality of pairs of leaves interposed between said rings, each leaf being pivotally mounted independent of all the other leaves on one of said rings, and means whereby the leaves are so connected to the stationary ring that the rotation of the rotatable ring will simultaneously move all the leaves, the leaves in each pair being substantially identical in outline but different from the outline of all the other leaves.

In testimony whereof, I have hereunto set my hand at Los Angeles, California, this 3rd day of July, 1918.

FRANK E. GARBUUT.
